UNITED STATES PATENT OFFICE.

ROBERT MUNN DIXON, OF EAST ORANGE, NEW JERSEY.

DESIGN FOR A PRESSURE-GAGE CASE.

SPECIFICATION forming part of Design No. 28,291, dated February 15, 1898.

Application filed December 18, 1896. Serial No. 616,223. Term of patent 7 years.

To all whom it may concern:

Be it known that I, ROBERT MUNN DIXON, of East Orange, in the county of Essex, State of New Jersey, have invented and produced 5 a new and original Design for Pressure-Gages, of which the following is a complete specification, reference being had to the accompanying drawings.

In the accompanying drawings, Figure I is 10 a front elevation of my pressure-gage case. Fig. II is a rear elevation of the same. Fig. III is a bottom plan view thereof.

My design consists in the unitary design of 15 the shape or configuration shown in the accompanying drawings.

Referring to the figures on the drawings, 1

indicates the face of my gage-case, 4 the back of the case, and 5 the annular side wall that unites the face and back of the case.

6 indicates a plane tangential face defined 20 by the ears 7, through which screw-holes 8 are provided.

What I claim is—

The design for a pressure-gage case substantially as hereinbefore shown and de- 25 scribed.

In testimony of all which I have hereunto subscribed my name.

ROBERT MUNN DIXON.
